UNITED STATES PATENT OFFICE.

THORSTEN NORDENFELT, OF WESTMINSTER, ENGLAND.

MACHINE-GUN.

SPECIFICATION forming part of Letters Patent No. 298,493, dated May 13, 1884.

Application filed May 23, 1883. (No model.) Patented in England October 14, 1882, No. 4,899; in France April 14, 1883, No. 154,872; in Germany April 20, 1883, No. 25,956; in Spain July 10, 1883; in Italy September 30, 1883, No. 15,723, and in Austria December 15, 1883, No. 27,846.

To all whom it may concern:

Be it known that I, THORSTEN NORDENFELT, a subject of the King of Sweden, residing at 53 Parliament Street, in the city of Westminster, England, have invented certain new and useful Improvements in Machine-Guns, (for which I have received Letters Patent in Great Britain, No. 4,899, dated October 14, 1882; in France, No. 154,872, dated April 14, 1883; in Germany, No. 25,956, dated April 20, 1883; in Spain, dated July 10, 1883; in Italy, No. 15,723, dated September 30, 1883, and in Austria, No. 27,846, dated December 15, 1883,) of which the following is a specification.

This invention has for its object improvements in machine-guns; and it relates especially to simplification of the construction and improvements of the details of that class of gun now well known as the "Nordenfelt gun," and which have the barrels arranged side by side in a horizontal plane in the fore part of a rectangular frame.

In the drawings annexed, Figure 1 is a plan partly in section, and Fig. 2 is a longitudinal and vertical section, of a seven-barreled gun constructed in accordance with my invention. Fig. 3 is a rear elevation of the same, and Fig. 4 is a transverse vertical section taken on the lines 1-1 and 2-2 in Fig. 1. Fig. 5 is a vertical section, Fig. 6 a rear elevation, and Fig. 7 a plan, of a portion of the center cross-piece of the frame with a part of one of the barrels and a portion of the cover. Fig. 8 is a side elevation, and Fig. 9 is a plan, of a portion of the fore part of the frame and of one of the barrels. Figs. 10 show details of the front cross-piece. Fig. 11 is a portion of a longitudinal section of a modification. Fig. 12 shows details of the hand and action levers. Fig. 13 is a plan showing details of the spreading mechanism. Fig. 14 is a longitudinal section, Fig. 15 is a plan, Fig. 16 is a rear elevation, and Fig. 17 is a transverse section, of a modification.

A A are the barrels; B, the front cross-piece, and C the center cross-piece, of the rectangular frame.

D is the cover which closes over the breech mechanism, and which, as in the ordinary Nordenfelt gun, has openings in it, through which the cartridges descend from a movable magazine into the gun. The cover is hinged at δ to the center cross-piece, C.

E is the action-block, and F F are the side bars of the rectangular frame, which, near their rear ends, also serve to guide the action-block in its movements to and fro.

G are the plungers by which the cartridges are thrust into the barrels and the breeches closed behind them. The plungers are armed with extractors, as usual, to draw the cartridge-cases out of the barrels.

H are the strikers or firing-pins for firing the cartridges.

I are the springs for throwing the strikers forward.

K is the action-lever, by which the parts are moved.

M is the cartridge-receiver, into which the cartridges fall from the magazine, and which carries the cartridges to the barrels. The cartridge-receiver has openings through it, as usual, for the delivery of the cartridge-cases when they are withdrawn from the barrels.

N is the trigger-comb, which retains and releases the strikers at the proper times.

O is a part of the support on which the gun is carried.

P is the upper end of the elevating-screw, connected with O by a universal joint.

Q is a clamp, also forming part of a spreading arrangement, hereinafter described.

T is the hand-lever for working the gun.

I will now proceed to explain the novel features which these parts present.

I have represented two different arrangements for fixing the barrels in their places. One of these is illustrated by the Figs. 5, 6, 7, 8, and 9. As shown in these figures, the barrels A are inserted from behind through the center cross-piece, C, and front cross-piece, B, of the frame, and kept in position by lugs α on their breech ends, and the cover D hinged to the top of the center cross-piece.

Another method of securing the barrels is represented in Figs. 1 and 2. The barrels are in the usual way screwed into the center cross-piece. The front cross-piece is then passed 5 over their muzzles and secured to the side arms of the frame by keys or bolts. The barrels have flats upon them, and corresponding projections on the front cross-piece prevent them unscrewing.

10 Figs. 10 show the forms of the holes and recesses in the cross-piece B, and of the flats upon the barrels, which render it impossible for the barrels to turn when the cross-piece is in its place and secured by the keys f'f'. The 15 action-block E, which holds the plungers G, firing-pins H, and firing-springs I, is so short that it does not, as heretofore, reach over the rear end of the frame when it is at its rear-most position. It is provided with a cam- 20 slot, e, on its under side, by which, through a friction-roller, k, on the action-lever K, it receives its sliding motion backward and forward.

At the front end of the action-block E, below the plungers, is a projecting plate, L, 25 carrying oblique studs l and l', which, working with corresponding inclines, m and m', in the cartridge-receiver M, shifts the cartridge-receiver at the end of the rearward and beginning of the forward motions of the action-block E, in order to feed the gun. The first movement places the recesses in the cartridge-receiver beneath the openings in the cover, so that cartridges may fall into them from the magazine, and the second movement carries 30 these cartridges to the barrels, ready to be thrust into them by the plungers G on the further advance of the action-block. The firing-pins H, each surrounded by its spring I, are placed in holes drilled through the action-block and part of the plungers, and protrude 35 behind the action-block, through the spring-bar e', which is in two pieces. They are each provided with a lug, h, on the under side, and these lugs are slanted or beveled off at their rear in order to move laterally the trigger-comb N, 40 which lies at the rear end of the frame. The trigger-comb is held to one side—say to the left—by a spring, n', and is provided with studs or lugs n for retaining the firing-pins. These studs or 45 lugs are slanted or beveled on one side to correspond with the slant on the firing-pin lugs h, which, being pressed against them in the rearward motion of the action-block E, moves the trigger-comb N to the right until the firing-pin lugs h have passed the cocking-lugs n. The 50 spring n' then brings the comb N to the left again, whereby the cocking-lugs n come in front of the lugs h on the firing-pins, retaining them during the forward motion of the action-block E, and until they are released by the action-lever K moving the trigger-comb N. The part of 55 the firing-pin above the lug is of a rectangular section, and enters a guiding-recess, d', in the rear part of the cover or frame, while the lug h 60 is working the trigger-comb N. The action of 65

the trigger-comb N is not dependent on the spring n', for if this trigger-comb spring n' should break or become weak its work will be performed by a beveled lug, e', on the action-block which comes in contact with the comb at 70 n', and works it over to the left as soon as the firing-pin lugs h have passed the lugs n on the trigger-comb. When the hand-lever T approaches its foremost position, the heel k' of the action-lever K comes in contact with a stud, n', 75 on the trigger-comb N, bringing this to the right, releasing the firing-pins or hammers H, and firing the shots. Further, in case of breakage or weakness of the trigger-comb spring n', there is another stud, n', on the comb, 80 which is touched by the same heel of the action-lever when this goes back again, bringing the comb to the left. This stud is so placed that the comb N is moved the required distance, and is then held in position by the heel 85 k' until it is time for it to be moved by the firing-pins. Sometimes, to shorten the mechanism by the length which the striker H in Fig. 2 projects through the spring-bar e', I form the striker with an arm, h', on its under 90 side to carry the lug h. This modification is shown in Fig. 11. The action-lever K, which, by the friction-roller k upon it, works the action-block E, is also made to lock the breech at the same time as it moves the trigger-comb N 95 for firing. This is done by rounding off both ends k' and k' of the lever K to a radius equal to their distance from the center of rotation, and having corresponding concave surfaces on the action-block E at e' and on the rear of the frame at f'. These surfaces are so arranged 100 that the front of the action-lever k' enters the concave e' on the action-block E when this is fully forward, and before the rear end, k', of the lever has commenced to move the trigger-comb 105 N. When the shots are fired, the blows caused by the explosion press the action-block E against the lever K, and the lever, being supported at the rear, transfers the blow to the frame.

Fig. 12 shows a vertical section through the boss of the action-lever and the socket on the frame into which the boss is received. It shows also, in elevation, a portion of the hand-lever and a stud upon it, which enters within 115 and engages with the boss of the action-lever. As will be seen, the action-lever K has a boss, k', which enters a socket, f', in a bracket on the frame. The boss k' is tubular, and a notch, k', is cut in the side of it at its lower part. 120 The hand-lever T has a stud, t, entering the hole in the action-lever boss, and it has also a lug, t', to correspond with the notch k'. The bracket is provided with a flange, f', underneath. It overlaps the socket k' on one 125 side, and serves for the lug t' to rest upon when the levers are in acting position. The hand-lever is thus kept in place, thus making cross-pins and split pins unnecessary for coupling the hand-lever to the action-lever. The hand-le- 130

ver is easily made to engage with the action-lever when the action-block has been removed, and when it is in place the two levers are securely locked together.

5 Fig. 13 is a plan of the parts concerned in producing the spreading movement, by which in the act of firing the position of the gun is slightly varied, so that all the shots may not be planted in the same place. The hand-lever T is provided with another lug or finger, t' , to work the spreading apparatus. There is a bracket, O , to which the elevating-screw P is fixed, and which remains stationary. This bracket is grooved to receive a dovetail or 15 guide, f' , at the rear end of the frame, and the frame can move horizontally upon it. An adjustable bolt or pin, Q , projects through the bracket, and the spreading-finger t' on the hand-lever acts upon it during the firing, pushing 20 against the bracket O , and as the bracket-plate is fixed to the carriage by the elevating-screw the gun moves. The bolt or pin Q is adjustable by a nut, q , on the rear side of the bracket, and graduated to the required spreading 25 for different distances. The spreading given by the apparatus is dependent upon the distance of the point q' of the pin Q , acted upon by the spreading-finger t' from the center of motion of the lever T —the farther the 30 bolt or pin is projected forward toward the center the less movement is imparted. After firing, the gun is brought back to its original position by the spreading-finger t' , acting at o' against a lug, o'' , on the bracket O . Thus the 35 bracket is brought up against the stop f' , and it is retained there during the further movement of the hand-lever by curved horn or lug o'' . The bolt or pin Q can also be used as a cramp to fasten the bracket O to the gun-frame when no spreading is required. The 40 bolt or pin Q is then drawn back until it is clear of the spreading-finger t' , and its head is made to enter a notch, f'' , in the frame.

Fig. 14 is a longitudinal and vertical section, Fig. 15 a plan, Fig. 16 a rear elevation, and Fig. 17 a transverse section, of a four-barreled gun of larger caliber. The cocking apparatus differs somewhat from that previously described.

50 I arrange the cocking mechanism so that the hammers or firing-pins H do not work the trigger-comb N to the side. I thereby save some of the labor which is required for overcoming the pressure of the trigger-comb spring.

55 Instead of having a spring to press the trigger-comb over to one side, I place a spring, S , along the rear side of the comb, in order to make the comb work somewhat stiffly. The 60 spring has a lug, and the trigger-comb two notches, n^4 n^4 , with which the lug engages. They are placed as far apart as the length of the stroke of the trigger-comb N . The lug on the trigger-comb, by means of which the 65 action-lever heel brings the comb back after firing, will in this case be dispensed with.

When the shots are fired, the trigger-comb N is placed so that the cocking-lugs n are clear of the firing-pin lugs h . The comb retains this position until after the firing-pin lugs h have 70 returned past the cocking-lugs n , and then the beveled lug e' on the action-block, acting against the incline n^3 , forces the comb N over to the other side, where it remains until the action-lever heel k' works it back for firing. 75 In this gun the cartridge-receiver M receives movement from the action-block E by means of a stud, l , at the end of an arm, L , projecting forward from the action-block. The stud l is contained in a central passage, m , provided in the cartridge-receiver M to receive it, and at m' the passage is inclined so that the stud, traversing the passage, may impart the desired movement to the cartridge-receiver. In this gun also the action-block is 85 locked, when the breech is closed, by bolts R R , pushed out from it into the frame. The bolts are controlled by a slotted lever rocking on a pivot, e^2 . The slotted lever receives movement from the end k^4 of the action-lever, as in 90 Nordenfelt guns at present in use.

Having thus described the nature of my said invention and the manner of performing the same, I would have it understood that I claim—

1. The combination of the frame, the barrels having supporting-connection therewith at front and having grooved lugs formed on their rear ends, the cross-piece C of the frame having recesses into which said lugs enter, and the cover provided with the enlargement received by the grooves of the barrel-lugs, substantially as and for the purpose hereinbefore set forth. 95

2. The combination of the frame, the barrels having supporting-connection therewith at rear and reduced at their front ends, and a front cross-piece, B , of the frame grooved and perforated within its groove to receive the reduced ends of the barrels, substantially as hereinbefore set. 105

3. The combination of the longitudinally-moving action-block having the projecting piece L , and inclines $l'l'$, and the transversely-moving cartridge-receiver having inclines m m' , actuated by the action-block, substantially 115 as and for the purpose hereinbefore set forth.

4. The combination of the strikers, the trigger-comb provided with the incline n^3 , and the action-block provided with an incline, n' , acting against the incline of the trigger-comb, 120 substantially as and for the purpose hereinbefore set forth.

5. The combination of the frame provided with the cavity f^2 , the action-block with the cavity e^2 , and the action-lever having ends k' k^4 , entering said cavities, substantially as and for the purpose hereinbefore set forth. 125

6. The combination of the frame provided with the socket f^3 , having the flange f^4 , the action-lever provided with the hollow boss k^2 , 130 entering the frame-socket, and the hand-lever T , having the stud t , entering the boss of the

action-lever, and provided with the lug bearing against the flange of the frame-socket, substantially as and for the purpose hereinbefore set forth.

5 7. The combination of the bracket O of the frame or carriage, the adjustable bolt or pin Q, and the hand-lever T, having the spreading

lug or finger, substantially as and for the purpose hereinbefore set forth.

THORSTEN NORDENFELT.
